UNITED STATES PATENT OFFICE.

THOMAS A. NORRIS, OF BROCKTON, MASSACHUSETTS.

PUNCHING-MACHINE.

SPECIFICATION forming part of Letters Patent No. 531,744, dated January 1, 1895.

Application filed March 9, 1894. Serial No. 503,001. (No model.)

To all whom it may concern:

Be it known that I, THOMAS A. NORRIS, of Brockton, in the county of Plymouth and State of Massachusetts, have invented a new and useful Improvement in Punching-Machines, which will, in connection with the accompanying drawings, be hereinafter fully described, and specifically defined in the appended claims.

10 In said drawings: Figure 1 is a side elevation of a punching machine embodying my invention; the base being in part broken away to show interior parts. Fig. 2 is a front elevation (taken at the right of Fig. 1) the base being in part broken away to show interior parts. Fig. 3 is a detached top plan view of the clearer, shown in Figs. 1 and 2. Fig. 4 is a detached under side or reverse plan view of the clearer, plate and gears. Fig. 5 is a detached plan view of the lower punching die, the stripper and the gage. Fig. 6 is an inverted or under side plan view of the top punching plate, with the punches therein inserted.

25 This invention relates to machines adapted to punch, in fancy patterns, the toe pieces of shoes; and it consists in means by which when the punches have passed through the leather the punch pieces or bits of leather cut out by 30 punching, are cleared away from the ends of the punches so that there is no danger, as there otherwise would be, of such bits of leather being drawn back by the punches and being then in the way of the next piece of 35 leather that is to be punched.

In said drawings A represents the punching machine, which may be of such form and proportion as will best accomplish the intended result. Said press embodies a pulley 40 B, secured on shaft C, which vertically drives the rod D, which at its upper end is secured to F that is loosely mounted on an eccentric wrist pin of said shaft, while its lower end is connected with a plunger G that reciprocates 45 in casing E. A plate a is secured to the lower end of plunger G and in said plate is secured a series of punches b arranged in such position as to impart to the punched leather the desired design when perforated by said 50 punches. Said punches pass through and move freely in clearer plate c and just through the bottom punch plate d. A plate e riveted

to plates c and d holds the two latter at the proper distance apart to admit the leather to be punched between them, and it serves as 55 a gage or stop for the leather. A belt H is driven by pulley B, and passing over trucks m in holder I it engages and drives pulley f, which is formed with a small gear g, which meshes with and drives the adjacent gears h, 60 h, Fig. 4. Said gears g and h are mounted in plate q and are for safety and convenience inclosed by a curb k, k. Said plate q is secured to body A by screws t and it is set at a proper position by the push screws 2 that bear 65 against body A in a well-known manner. The studs 3 that carry gears g and h, have secured to their upper ends the central clearer i and the side clearers j, as shown in Fig. 3; said central clearer being formed with five wings 70 or members and the clearers j with four wings so that they pass the one within the other and yet do not come in contact. Said clearers are, by means of screws t and 2, arranged to move close to the under side of plate d so 75 that as the leather punchings are carried through said plate the clearers sweep them away so that when the punches rise they cannot bring said punchings back, as they otherwise would often do. 80

It will be apparent that instead of employing the form of clearers shown, other forms may be used, and that instead of their rotating as shown they may be arranged to reciprocate in such manner as to accomplish 85 the intended result.

If it is desired to give the clearers i and j a capacity to slightly recede from plate d and to then return to their former position, such action may be secured by means of springs 90 4, which may be secured in sleeves l so as to tend constantly to press said clearers upward, yet allowing their being depressed for the moment if they encounter a punching that is not fully forced down through plate d. Said 95 sleeves l are formed as shown to allow said limited upward and downward play of the clearers, which in some classes of work is very desirable.

Having thus described my invention, what 100 I claim, and desire to secure by Letters Patent, is—

1. In a punching machine, and in combination with a series of reciprocating punches,

a clearer arranged to move over the punch plate to remove the punchings therefrom as they pass through said plate, substantially as specified.

5 2. In combination with punch plate *d* and the co-acting punches *b*, the clearers *i, j*, arranged to revolve close to said plate, and the gears *g, h, h*, arranged on the stems of said clearers and driven by belt *H*, substantially as specified.

3. In combination with clearers *i, j* the springs 4, arranged below the clearers and ar-

ranged to exert a constant upward tendency thereon yet allowing a limited downward action thereto, substantially as specified. 15

4. In a punching machine the combination of punches *b*, stripper plate *c*, punch plate *d*, and clearers *i, j*, all operating substantially as specified.

THOMAS A. NORRIS.
